UNITED STATES PATENT OFFICE.

OLIVER B. HALSTEAD, OF NEAR ONTARIO, CALIFORNIA.

ORCHARD HEATER.

Application filed May 22, 1922. Serial No. 562,821.

To all whom it may concern:

Be it known that I, OLIVER B. HALSTEAD, a citizen of the United States, residing at near Ontario, in the county of San Bernardino and State of California, have invented a new and useful Orchard Heater, of which the following is a specification.

This invention relates to heaters for use in orchards and the like.

10 The object of the invention is to provide a simply constructed and efficient heater of this character which may be readily transported from place to place and which will effectively heat a large area surrounding it with a minimum consumption of fuel.

20 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

25 In the accompanying drawings:—

Figure 1 represents a central vertical section of the casing constituting part of this heater with the other parts shown in side elevation and partly in section.

30 Fig. 2 is a horizontal section taken on the line 2—2 of Fig. 1.

Fig. 3 is a view similar to Fig. 1, showing a modified form of the invention, and

35 Fig. 4 is a horizontal section taken on the line 4—4 of Fig. 3.

40 In the embodiment illustrated in Figs. 1 and 2, a sheet metal casing 1 is shown which may be circular in cross section or of any other desired configuration, and which is equipped with a removable dome-like cover 2.

45 Mounted in the casing 1 is an oil burner 5 having a supply pipe 6 leading from a container (not shown) and which extends into the casing at a point near the bottom thereof. This inlet pipe 6 is connected with an upright pipe 7 by an elbow coupling 7^a. This upright pipe 7 merges at its upper end into a U-shaped horizontally disposed pipe which includes legs 8 and 10 connected by a cross bar 9. A vertical pipe 11 is connected with the free end of leg 10 by a suitable elbow coupling and at its lower 55 end is connected by a coupling 11^a with a horizontally disposed pipe 12 having an

aperture 13 in its upper wall for a purpose presently to be described.

The horizontal pipe 12 is connected by an elbow 12^a with an upright pipe 14 which extends to a point near the top of the casing 1 and is provided near its upper end with a plurality of radially opening apertures 15 through which the gas generated in the horizontal pipes passes and is ignited.

In the use of this heater, oil is fed in through pipe 6 and passes up through pipe 7 around through the U-shaped pipe down through the vertical pipe 11 into the lower horizontal pipe 12 and is ignited at 13, the flame formed by this ignition contacting with the upper horizontal pipe and with a plate 16 which connects the legs 8 and 10 of the U-shaped pipe and the heat contacting with these members generates gas which flows down through pipe 11, enters pipe 12 and passes up through pipe 14 and is ignited at 15 by the flame from below. This arrangement of pipes and the heat generated by the burning liquid fuel and the gas is extreme and passes out through apertures at the base of the top 2 to the surrounding atmosphere as well as by radiation from the casing 1 so that a large area around the heater is heated sufficiently to prevent freezing in the orchard in which the device is located. It will also be seen that such a heater will consume a comparatively small amount of oil.

55 In the form of heater shown in Figs. 3 and 4 a casing 1^a of sheet metal is shown equipped with a spider top 2^a in which is mounted a burner in the form of a coiled pipe 5^a having an aperture 18 in the upper wall of one of the lower parts of the coil as is shown clearly in Fig. 4, and through which the oil exudes and is ignited for heating the oil in the surrounding coils 17 and the gas passes upward through pipe 19 and is ignited at the upper end thereof, the flame formed at this end contacting with the top 2^a and is diffused over a large area.

60 An inlet pipe 6^a extends through one side wall of the casing 1^a and merges into the coil 5^a at the upper portion thereof so that the oil entering through this pipe 6^a will pass around through the respective coils 17 and that portion which passes through the aperture 18 will be ignited and heat the coil sufficiently to generate gas which as above described passes out through pipe 19 and is ignited to form the heating flame.

This form of heater like that shown in Figs. 1 and 2 is very simple in construction, utilizes a minimum amount of fuel, produces a maximum amount of heat and both of them may be readily transported from place to place to supply heat where needed.

I claim:—

1. A heater of the class described comprising a sheet metal casing having a spreader-like closure at its upper end with heat outlets at the base of said closure, a gas generator mounted therein and including oil conduits arranged one above the other, the lowermost having an opening positioned under the upper and adapted for the passage of fuel therethrough to be used in heating the oil in the pipes above to generate gas, and a gas pipe leading from said generator and having a burner at its upper end.
2. A heater of the class described comprising a sheet metal casing having a removable overhanging closure at its upper end with openings formed under the over-

hanging portion thereof, a gas generator mounted in said casing and comprising a supply pipe entering through one side wall thereof, an upright pipe connected with said supply pipe, a horizontally disposed U-shaped pipe connected at one end with said upright pipe, another pipe depending from the other end of said U-shaped pipe, a horizontal pipe carried by said depending pipe, an upstanding pipe leading from said last mentioned pipe and having a burner at its upper end, and an aperture in one of said lower pipes for the outlet of oil to be burned and by means of which the oil in the other pipes is heated.

In testimony that I claim the foregoing as my own, I have hereto affixed my signature in the presence of two witnesses.

OLIVER B. HALSTEAD.
